TRAVELING OFFSET WEB CONTROLLING
MECHANISM FOR MULTICOLOR PRINT-
ING PRESSESHoward M. Barber, of Pawcatuck, Conn., as-
signor to C. B. Cottrell & Sons Company, of
Westerly, R. I., a Corporation of Delaware

Application July 1, 1931. Serial No. 548,137

15 Claims. (Cl. 101—417)

It has been very difficult in multicolor web perfecting rotary printing presses to obtain clean and sharp printing because of the tendency of slippage between the offset web and printed web as they are passing around the impression cylinder of the second printing unit. This was pointed out in my United States Letters Patent No. 1,806,141, dated May 19th, 1931, and an offset web controlling mechanism for obviating this fault was disclosed and claimed therein.

The object of this present invention is to ensure clean and sharp printing by providing an offset web controlling mechanism which engages the traveling offset web both before and after it passes through the second printing unit and acts to exert tension tending to slightly retard the offset web, thus eliminating slippage between the webs as they pass around the impression cylinder of the second printing unit.

My invention more particularly includes an offset web controlling mechanism having a positively driven web tension element engaging the offset web before it passes around the impression cylinder of the second printing unit and another positively driven web tension element engaging the offset web after it leaves the impression cylinder and before it reaches the offset web rewinding mechanism.

My invention also includes a manually controlled variable speed drive for the offset web control mechanism for regulating the speed of the offset web, said variable speed drive being itself driven from the printing unit.

A practical embodiment of my invention is represented in the accompanying drawing in which:

Fig. 1 represents a diagrammatic side elevation of that portion of a multicolor web perfecting rotary printing press which embodies my invention; and

Fig. 2 represents a detail top plan view showing the variable speed drive unit for the offset web controlling mechanism.

In the printing press illustrated, four form cylinders 1, 2, 3, 4 are represented as driven from and coacting with the impression cylinder 5. The traveling printed web is denoted by 6 and the traveling offset web by 7, which offset web is shown as leading from the supply roll 8 around

the impression cylinder 5 to the take-up roll 9 of the offset web rewinding mechanism.

This rewinding mechanism in the present instance is shown as comprising a pair of rollers 10, 11, driven from the gear 12 on the shaft of 55 the impression cylinder 5 through the train of gears 13 to 21 inclusive.

The offset web controlling mechanism is herein shown as comprising three positively driven offset web tension rolls 22, 23, 24. The offset web 60 as it leaves its supply roll 8 passes to and around a roller 25 and from thence back and around the web tension roll 22 of the offset web controlling mechanism. From thence the offset web passes around the rollers 26, 27 to and around the impression cylinder 5. From thence the offset web passes around the rollers 28, 29 to and around the web tension rolls 23, 24 of the offset web controlling mechanism. From the web tension roll 24 the offset web passes around the rollers 30, 31, 32 to the offset web take-up roll 9. 70

The web tension rolls 22, 23 and 24 of the offset web controlling mechanism are driven at the same surface speed through the intermeshing gears 33, 34, 35. These web tension rolls are positively driven from a manually controlled variable speed drive such as the well known "Reeves" drive in which the shaft 36 is driven at a constant speed by the meshing of its gear 37 with the gear 19 of the train of gears leading from the second printing unit to the offset web rewinding mechanism. The shiftable cone pulleys 38 on the constant speed shaft 36 drive the shiftable cone pulleys 39 on the shaft 40 through the usual belt 41. This shaft 40 drives the shaft 41 of the retarding roll 23 through the chain and sprocket connection 42, 43, 44. The manually operated means for varying the speed of the shaft 40 is denoted as a whole by 45. 80

The printed web is taken off from the impression cylinder 5 by the roll 46 whose gear 47 is driven from the gear 14 of the train of gears leading from the impression cylinder gear 12 to the offset web rewinding mechanism. 90

I have found that by providing the offset web controlling mechanism with positively driven web tension elements engaging the offset web before and after it passes around the impression cylinder of the second printing unit the offset web is effectively controlled so that there will 100

be no slippage between it and the printed web as they pass around the impression cylinder, thus ensuring the clean and sharp printing of the product.

5 The linear speed of the offset web is controlled by the offset web tension rolls 22, 23 and 24 and not by the surface speed of the impression cylinder 5. These offset web tension rolls 22, 23 and 24 have the same surface speeds, which speeds 10 are slightly less than the surface speed of the impression cylinder 5. Therefore, there is a slight slippage of the offset web on the impression cylinder 5 which is sufficient to prevent any slippage between the offset web and the printed web.

15 It is evident that various changes may be resorted to in the construction, form and arrangement of the several parts without departing from the spirit and scope of my invention, and hence 20 I do not intend to be limited to the particular embodiment herein shown and described, but

What I claim is:

1. In a multicolor web perfecting rotary printing press, a printing unit, a traveling offset web, its rewinding mechanism, and an offset web controlling mechanism engaging the offset web both before and after it passes through the printing unit, to exert tension tending to slightly retard the web.

25 2. In a multicolor web perfecting rotary printing press, a printing unit, a traveling offset web, its rewinding mechanism, and a positively driven offset web controlling mechanism engaging the offset web both before and after it passes through the printing unit, to exert tension tending to slightly retard the web.

30 3. In a multicolor web perfecting rotary printing press, a printing unit, a traveling offset web, its rewinding mechanism, and an offset web controlling mechanism engaging the offset web both before and after it passes through the printing unit, to exert tension tending to slightly retard the web, said offset web controlling mechanism including a variable speed drive.

35 4. In a multicolor web perfecting rotary printing press, a printing unit, a traveling offset web, its rewinding mechanism, and a positively driven offset web controlling mechanism engaging the offset web both before and after it passes through the printing unit, to exert tension tending to slightly retard the web, said offset web controlling mechanism including a variable speed drive.

45 5. In a multicolor web perfecting rotary printing press, a printing unit, a traveling offset web, its rewinding mechanism, and an offset web controlling mechanism engaging the offset web both before and after it passes through the printing unit, to exert tension tending to slightly retard the web, said offset web controlling mechanism including a manually adjustable variable speed drive.

55 6. In a multicolor web perfecting rotary printing press, a printing unit, a traveling offset web, its rewinding mechanism, and a positively driven offset web controlling mechanism engaging the offset web both before and after it passes through the printing unit, to exert tension tending to slightly retard the web, said offset web controlling mechanism including a manually adjustable variable speed drive.

65 7. In a multicolor web perfecting rotary printing press, a printing unit, a traveling offset web, its rewinding mechanism driven from the printing unit, and an offset web controlling mecha-

nism also driven from the printing unit and engaging the offset web both before and after it passes through the printing unit, to exert tension tending to slightly retard the web.

80 8. In a multicolor web perfecting rotary printing press, a printing unit, a traveling offset web, its rewinding mechanism driven from the printing unit, and an offset web controlling mechanism also driven from the printing unit and engaging the offset web both before and after it passes through the printing unit, to exert tension tending to slightly retard the web, said offset web controlling mechanism including a variable speed drive also driven from the printing unit.

85 9. In a multicolor web perfecting rotary printing press, a printing unit, a traveling offset web, its rewinding mechanism driven from the printing unit, and an offset web controlling mechanism also driven from the printing unit and engaging the offset web both before and after it passes through the printing unit, to exert tension tending to slightly retard the web, said offset web controlling mechanism including a manually adjustable variable speed drive also driven from the printing unit.

90 10. In a multicolor web perfecting rotary printing press, a printing unit, a traveling offset web, its rewinding mechanism, and an offset web controlling mechanism having a positively driven element engaging the offset web before it passes through the printing unit and another positively driven element engaging the offset web after it leaves the printing unit, to exert tension tending to slightly retard the web.

105 11. In a multicolor web perfecting rotary printing press, a printing unit, a traveling offset web, its rewinding mechanism, and an offset web controlling mechanism having a positively driven element engaging the offset web before it passes through the printing unit and another positively driven element engaging the offset web after it leaves the printing unit, to exert tension tending to slightly retard the web, said offset web controlling mechanism including a variable speed drive.

115 12. In a multicolor web perfecting rotary printing press, a printing unit, a traveling offset web, its rewinding mechanism, and an offset web controlling mechanism having a positively driven element engaging the offset web before it passes through the printing unit and another positively driven element engaging the offset web after it leaves the printing unit, to exert tension tending to slightly retard the web, said offset web controlling mechanism including a manually adjustable variable speed drive.

125 13. In a multicolor web perfecting rotary printing press, a printing unit, a traveling offset web, its rewinding mechanism, and an offset web controlling mechanism having a positively driven roll around which the offset web passes before reaching the printing unit and other positively driven rolls around which the offset web passes after it leaves the printing unit, to exert tension tending to slightly retard the web.

135 14. In a multicolor web perfecting rotary printing press, a printing unit, a traveling offset web, its rewinding mechanism, and an offset web controlling mechanism having a positively driven roll around which the offset web passes before reaching the printing unit and other positively driven rolls around which the offset web passes after it leaves the printing unit, to exert tension tending to slightly retard the web, said

offset web controlling mechanism including a variable speed drive.

15. In a multicolor web perfecting rotary printing press, a printing unit, a traveling offset web, its rewinding mechanism, and an offset web controlling mechanism having a positively driven roll around which the offset web passes before

reaching the printing unit and other positively driven rolls around which the offset web passes after it leaves the printing unit, to exert tension tending to slightly retard the web, said offset web controlling mechanism including a manually adjustable variable speed drive. 80
